WIRE FABRIC WEAVING MACHINE

Noah S. Harter, Waukegan, Ill., assignor to Cyclone Fence Company, Waukegan, Ill., a corporation of Illinois

Application August 23, 1934, Serial No. 741,158

9 Claims. (Cl. 139—115)

The invention relates to automatic weaving machines for manufacturing wire screen fabric and has particular reference to improved apparatus for maintaining the warp wires at the proper tension.

Among the objects of the invention is to provide improved apparatus for automatically feeding the warp wires to the machine in proportion to the amount of completed wire screen taken from said machine to thus maintain the warp wires under the proper tension necessary for the weaving operation.

Another object is to provide a movable supporting member for the warp wires which will have periodic movement to vary the tension on said wires to counteract the action of certain operations thereon, thereby maintaining the wires under substantially uniform tension during the weaving operation.

Another object is to provide mechanism that will operate upon the slightest variation in the tension of the warp wires to interrupt or re-establish the feeding of the warp wires to maintain the proper tension on said wires necessary for the weaving of perfect fabric.

With these and various other objects in view, the invention may consist of certain novel features of construction and operation, as will be more fully described and particularly pointed out in the specification, drawings and claims appended hereto.

In the drawings which illustrate an embodiment of the invention and wherein like reference characters are used to designate like parts—

Figure 1 is an elevational view of a weaving machine embodying the features of the present invention;

Figure 2 is an elevational view of the machine looking toward the side opposite that of Figure 1;

Figure 3 is a horizontal sectional view taken substantially along line 3—3 of Figure 1;

Figure 4 is a plan view of the weaving machine shown in Figure 1; and

Figure 5 is a vertical sectional view through the machine and showing the drive for various operating members of the machine.

Referring to Figures 1 and 2 of the drawings numerals 10 and 11 designate the side frames of a wire weaving machine having a plurality of feeding or let-off rollers 12 carried by shafts 13 journaled by the side frames at the rear of the machine for feeding a plurality of wires 14 forming the warp wires of the fabric. A gear 15 is secured to one end of each shaft 13 and operatively connects the shafts so that the rollers rotate in unison

and at the same speed. Take-up rollers 16 carried by shafts 17 are journaled by the side frames at the forward end of the machine and receive the completed fabric 18 from the delivery roller 20. A gear 21 is secured to one end of each of the shafts 17 to operatively connect the shafts so that these rollers are also driven in unison and at the same speed. Rotation of the take-up rollers 16 withdraws from the machine the completed fabric which travels under the machine and is subsequently wound upon a drum, not shown, located a distance from the rear.

Each of the side frames 10 and 11 provide a bearing 22 for pivotally supporting a member 23 forming the supports for the beater frame designated in its entirety by 24. The beater frame is oscillated back and forth in the direction of travel of the warp wires 14, being actuated by arms 25 pivoted to the respective sides of the frame at 26 and which arms pivotally connect at their opposite ends with a crank 27 and gear wheel 28, respectively. Said crank and gear are secured to the respective ends of a transverse shaft 30 journaled by the side frames. Shaft 30 is driven from the motor 31, Figure 3, having pinion 32 secured to its rotor shaft and which meshes with gear 33 on the clutch shaft 34 journaled by side frame 11 and bracket 35. To the outer end of this shaft is secured a hand wheel 36 and to the inner end is secured pinion 37 having meshing engagement with gear 28. The shaft is provided with a clutch designated in its entirety by 38 and which is actuated by rod 40 extending to the front of the machine and connecting with handle 41. Actuation of said handle will therefore operatively connect transverse shaft 30 with the electric motor 31 to cause the desired operation of the beater frame 24.

Carried by the frame, as shown in Figure 4, are spaced lays 42 which position a plurality of reed dents 43 through which the warp wires extend. Also carried by the outwardly extending supports 44 fixed to the beater frame are the shuttle bars 45 which oscillate to carry the bobbin or weft wire across the beater frame, whereby the same is woven with the warp wires to form the completed fabric. The actuating mechanism for the shuttle bars, which is driven from transverse shaft 46 through a chain of gears, not shown, comprises a shaft 47 rotatably journaled in the spaced bracket members 48 supported from the frame members by transverse beams, Figure 5, and having crank arms 49 secured to the ends thereof. The gear racks 50 have one end pivotally connecting with the crank arms 49 and mesh with pinions 55

51 secured to the shaft 52. Centrally of said shaft are secured spaced sprockets 53, each of which drive a chain 54, Figure 4, which meshes at its opposite end with sprocket 55 having arms 56. Each arm connects with a gear rack 57 extending transversely of the machine and meshing with pinion 58, actuating mechanism, not shown, and operatively connecting with the shuttle bars 45. Rotation of shaft 46 will cause reciprocation 10 of gear racks 50 and partial rotation of shaft 52, first in one direction and then in the reverse direction. The rotations of this shaft are transmitted by chain 54 to arms 56 which in turn oscillate the gear racks 57 rotating the pinions 58 to 15 in turn cause the desired actuation of the shuttle bars.

The warp wires from the feeding rollers 12 are directed over an adjustable roller 60 journalled in members 61 pivoted at 62 to blocks 63 mounted 20 within guides 64 formed in the side frames and vertically adjusted within said guides by rotation of the threaded screw 65. From roller 60 the wires pass over and under the spaced transverse bars 66 supported by uprights 67. Between 25 the bars 66 and the beater frame the warp wires alternately connect with heddles 68 located in frames 10 supported for vertical reciprocating movement by members 71, Figure 2, secured to the respective side frames. The heddle frames 30 are carried from the portion 72, connecting the side frames, by means of chains 73 which mesh with sprockets 74 secured to shaft 75 journalled by said portion. The heddle frames are located adjacent each other and each operatively connect 35 through chain 73 with shaft 75. As one heddle frame descends the connection through chain 73 will cause the other frame to ascend and vice versa. The frames are vertically reciprocated by the rods 76 which connect at their upper end with 40 the heddle frames, as shown in Figure 1, and at their lower end with levers 77 supported at 78 for pivotal movement and which are actuated by cams 79 secured to transverse shaft 80 driven from shaft 46, by gears not shown.

45 The feed rollers 12 are driven through means which will now be described to cause feeding of the warp wires to the machine in proportion to the amount of completed fabric removed from the machine by the rotation of the front rollers 16. Secured to the lower of the rear shafts 13 carrying the feeding rollers is a gear 81 meshing with worm gear 83 journalled in supports 84 integral with side frame 10. Gear 83 carries pinion 85 meshing with pinion 86 secured to the end of the connecting rod 87 supported for rotation from side frame 10. Secured to one of the shafts 17, carrying the front rollers 16, is a gear 88 meshing with worm gear 89 on shaft 90 suitably journalled by the side frame and carrying gear 91. Gear 92 is rotatable on rod 87 and meshes with gear 91. A clutch 93, held in operative position by coil spring 94, connects gear 92 with operating rod 87 and completes the drive from the front rollers to the feed rollers at the rear of the machine.

The shaft 95 journalled in side frame 10 and bracket 96, Figure 3, has the gear 97 secured to the outer end thereof and pinion 98 secured to its inner end. Said pinion meshes with gear 99 secured to the right hand end of transverse shaft 46 which is driven from shaft 30 through idler 100 having meshing engagement with gear 99 on the left end of shaft 46 and pinion 102 on shaft 30. Gear 97, carried by shaft 95, is therefore driven from the electric motor 31 and in turn

drives shaft 102 as the same has meshing engagement with gear 103 secured thereto. Said shaft is journalled in bracket 104 and side frame 10 and carries bevel pinion 105 meshing with bevel pinion 106 on shaft 107, which operatively connects with shaft 90 to drive the front rollers and rod 87 to drive the feed rollers. The rollers are therefore driven through the gearing described to cause travel of the completed fabric over the rollers and removal of the same from the machine. 10

The invention provides improved mechanism for interrupting the drive to the rollers in timed relation to the operations of the machine and particularly the beater frame since the fabric must be removed from weaving machines of the present type at intervals and in equal amounts to secure the proper spacing of the weft wires. The structure comprises a cam 108 secured to gear 97 and rotated by shaft 95 and which cam carries a portion 109 provided with a cam surface 20 and adjustable with respect to cam 108. The cam has engagement with arm 110 pivoted to bracket 104 and held in contact with the cam by the resilient means 111 and which is connected by means of rod 112 with the operating lever 113 of 25 clutch 114 on shaft 107. As a result of the rotation of cam 108 arm 110 is rocked back and forth, causing similar actuation of lever 113 and operation of clutch 114 to interrupt the drive to the rollers. The removal of the completed fabric and 30 the feeding of the warp wires to the machine therefore occurs intermittently and in timed relation to the weaving operations. The duration of the interruption and therefore the amount of fabric removed during each interval can be varied 35 by adjustment of cam portion 109 with respect to cam 108.

As the coil spring 94 yieldingly maintains clutch 93 in engagement to connect the operating shaft 87 with gear 92 it will be understood 40 that the feed rollers 12 can have rotation in amounts equal to that of the front rollers 16. The feeding of the warp wires under these conditions is therefore in proportion to the amount of completed fabric removed from the machine, 45 and should theoretically result in maintaining the wires passing through the machine under substantially uniform tension. However, the tension varies to a considerable extent due to the weaving operations on the wire and to other inaccuracies inherent in the operation and design of the machine. In this connection the invention provides means sensitive to slight variations in the tension of the warp wires for automatically interrupting and reestablishing the 50 drive to the rear feed rollers which are driven intermittently in synchronism with the front rollers so that the feeding of the warp wires occurs 55 as demanded by the tension of said wires.

Clutch 93 is provided with an actuating lever 60 115 secured to rotatable rod 116, Figure 5, having lever 117 located to the inside of frame 10. Rotation of lever 117 in a clockwise direction will actuate the clutch 93 against tension of spring 94 to release the clutch, disconnecting rod 87 from gear 92. Formed integral with one of the supporting members 61 for the oscillating roller 60 is an arm 118 having an extension flange supporting an upright 119. On the respective sides of arm 118 to the inner end thereof are pivoted levers 120 journalled at their outer end a roller 121. One lever carries a pivoted bell crank 122. Upright 119 receives a coil spring 123 which is confined between the levers and the upper securing nut 124. Pivotal movement of the levers 75

120 with respect to arm 118 can only take place against the tension of spring 123, or, in other words, said coil spring tends to maintain the levers and arm in parallel relation and prevents their separation by pivotal movement. The levers 120 are oscillated as roller 121 contacts cam 125 secured to shaft 30. The rocking movements of the lever are transmitted to roller 60 over which the warp wires pass. This movement of the roller is, however, in a direction substantially parallel to the travel of the warp wires, with the result that movement of the roller in one direction will have the effect of increasing the tension on said wires, while movement in the opposite direction will have the effect of decreasing said tension. These operations occur in synchronism with the movements of the heddle frames which connect with alternate warp wires, causing separation of the same vertically to permit passage 20 through the warp shed of the shuttle bars carrying the bobbin. As the wires are caused to separate roller 60 is rocked counter-clockwise to relieve the tension on said wires and as the frames approach their median position prior to separation in the opposite direction the roller is rocked clockwise to increase the tension on the wires. The combined result is to maintain a substantially uniform tension on the warp wires.

In the event the tension on the wires should decrease to below a set limit the levers 120 will assume a parallel relation with arm 118 rotating the bell crank 122 counter-clockwise as one leg of said crank rests on flange 126 secured to the arm. This movement of the bell crank is imparted to rod 121 secured to the other leg of the bell crank and pivotally connected at its opposite end to lever 117. It will be noted that rotation of the bell crank and corresponding actuation of rod 127 is in a direction to release the clutch 93, interrupting the drive to the feed rollers. As removal of the completed fabric from the machine continues the tension on the warp wires will immediately increase and as roller 60 is again rotated clockwise levers 120 and arm 118 will separate, resulting in a scissors action to allow crank arm 122 to assume its former position, again establishing the drive to the feed rollers. From the foregoing it will be clear that the scissors action of levers 120 and arm 118 is responsive to variations in the tension of the warp wires and which is immediately and automatically taken care of by the actuation of clutch 93 to interrupt or reestablish the drive to the feed roller. The operations are extremely sensitive to the slightest variation in the tension of the warp wires so that the actuation of the clutch 93 is for a moment only and the interruption of the drive to the feed rollers lasts for only a fraction of the interval during which the front rollers are rotated. Adjustment of the tension of the warp wires is provided for by the coil spring 123 which controls the scissors action of the levers and arm. The lever 128 provides for manual actuation of the clutch 93 which can be used for initially starting the machine to secure that tension on the warp wires needed for weaving perfect fabric or for correction of the tension during operation. Another provision for manually actuating the feed rollers comprises shaft 130 extending forwardly of the machine and secured to gear 92. By applying a crank to said shaft, rod 87 can be rotated to feed warp wires to the machine or to reverse their travel and back feed the fabric into the machine.

75 I claim:

1. In a machine for weaving wire fabric, in combination, rollers for feeding the warp wires to said machine, take-up rollers for removing the completed fabric, vertically reciprocating heddles engaging with the wires between said rollers and alternating the position of said wires to form the warp shed, a guide roller contacting the warp wires in advance of said heddles, means pivotally supporting said roller for oscillating movement to counter-act the actions of the weaving operations, an arm extending from said supporting means, a lever pivoted to said arm and resiliently connected thereto at its end to prevent separation of the arm and lever, and cam means contacting the end of said lever to yieldingly rock the guide roller. 5 10 15

2. In a machine for weaving wire fabric, rollers for feeding the warp wires to said machine, take-up rollers for removing the completed fabric, a guide roller engaging the warp wires as they leave the feeding rollers, means pivotally supporting said roller for oscillating movement in a direction substantially parallel to the travel of the warp wires, members pivoted to the supporting means and engaging a rotating cam causing actuation thereof, and resilient means connecting the members to the supporting means to prevent relative movement of the same whereby actuation of the members is yieldingly transmitted to cause oscillating movement of the roller, said movement of the roller occurring in timed relation with other operations of the weaving machine and maintaining a substantially uniform tension on the warp wires. 20 25 30

3. In a machine for weaving wire fabric, rollers for feeding the warp wires to said machine, take-up rollers for removing the completed fabric, a guide roller engaging the warp wires as they leave the feeding rollers, means pivotally supporting said roller for oscillating movement in a direction substantially parallel to the travel of the warp wires, an arm extending from said supporting means, levers pivoted to said arm and engaging a rotating cam, and a coil spring connecting the levers and arm preventing relative movement whereby the actuation of the levers by said cam is yieldingly imparted to the roller causing oscillating movement of the same, said movement of the roller occurring in timed relation with other operations of the weaving machine and maintaining a substantially uniform tension on the warp wires. 35 40 45 50

4. In a machine for weaving wire fabric, in combination, rollers for feeding warp wires to said machine, take-up rollers for removing the completed fabric, vertically reciprocating heddles engaging the wires between said rollers and alternating their position to form the warp shed, a guide roller contacting the warp wires in advance of said heddles and as they leave the feeding rollers, means supporting said roller for pivotal movement to increase or decrease the tension on the warp wires to counter-act the action of the reciprocating heddles, thereby maintaining a substantially uniform tension on the wires, an arm extending from the supporting means for the roller and providing means for oscillating the same, said arm being resiliently actuated by cam means rotating in synchronism with the weaving operation, and means having association with said arm for controlling the extent of rotation of the feeding rollers. 55 60 65 70

5. In a machine for weaving wire fabric, rollers for feeding warp wires to said machine, take-up rollers for removing the completed fabric, 75

means driving the take-up rollers intermittently to remove the fabric at intervals, a pivotally supported guide roller engaging the warp wires as they leave the feed rollers and having rocking movement to counter-act the action of the weaving operations, thereby maintaining a substantially uniform tension on the wires, means resiliently oscillating said roller in timed relation with the weaving operations, and control means associated with said resiliently oscillating means for controlling the drive to the feeding rollers to vary the extent of rotation imparted to the feeding rollers.

6. In a machine for weaving wire fabric, in combination, rollers for feeding warp wires to said machine, take-up rollers for removing the completed fabric, a guide roller over which the wires pass after they leave the feeding rollers, means supporting the guide roller for oscillating movement to counter-act the actions of the weaving operations, thereby maintaining a substantially uniform tension on the warp wires, an arm extending from the supporting means for the roller, members pivoted to the arm and having actuation to impart oscillating movement to said guide roller, resilient means holding the arm and members against relative movement whereby the roller is yieldingly oscillated, and means responsive to the extent of relative movement between the arm and members for controlling the drive to the feed rollers to vary the extent of rotation imparted to said feed rollers.

7. In a wire weaving machine, in combination, rollers for feeding warp wires to the machine, take-up rollers for removing the completed wire fabric, an intermittent drive for the take-up rollers whereby they remove the completed fabric at intervals, means including a clutch for driving the feeding rollers from the take-up rollers, a guide roller supported for oscillating movement and contacting the warp wires as they leave the feeding rollers, means oscillating said guide

roller through members resiliently held against relative movement, and means responsive to the tension of the warp wires as transmitted through the members for effecting actuation of the clutch thereby controlling the drive to the feeding rollers.

8. In a wire weaving machine, in combination, rollers for feeding warp wires to the machine, take-up rollers for removing the completed wire fabric, an intermittent drive for the take-up rollers whereby they remove the completed fabric at intervals, means including a clutch for driving the feeding rollers from the take-up rollers, a guide roller supported for pivotal movement and contacting the warp wires as they leave the feeding rollers, means yieldingly rocking the guide roller to counter-act the operations of the weaving machine, thereby maintaining a substantially uniform tension on the wires, and a connection from said means to said clutch, said connection effecting actuation of said clutch to control the drive to the feeding rollers in response to tension of the warp wires.

9. In a wire weaving machine, in combination, rollers for feeding warp wires to the machine, take-up rollers for removing the completed wire fabric, an intermittent drive for the take-up rollers whereby they remove the completed fabric at intervals, means including a clutch for driving the feeding rollers from the take-up rollers, a guide roller supported for pivotal movement and contacting the warp wires as they leave the feeding rollers, means yieldingly rocking the guide roller to counter-act the operations of the weaving machine, thereby maintaining a substantially uniform tension on the wires, said means including pivoted members yieldingly held against relative movement, and a connection from said means to said clutch having actuation upon relative movement of the members to thereby control the drive to the feeding rollers.

NOAH S. HARTER.
